UNITED STATES PATENT OFFICE.

JOHN RAPHAEL ROGERS, OF BROOKLYN, NEW YORK, ASSIGNOR TO MERTENTHALER LINOTYPE COMPANY, A CORPORATION OF NEW YORK.

LINOTYPE-MACHINE.

No. 845,196.

Specification of Letters Patent.

Patented Feb. 26, 1907.

Application filed October 15, 1906. Serial No. 338,951.

To all whom it may concern:

Be it known that I, JOHN RAPHAEL ROGERS, of the borough of Brooklyn, county of Kings, and State of New York, have invented 5 a new and useful Improvement in Linotype-Machines, of which the following is a specification.

My invention has reference to line-casting machines of the general organization represented in Letters Patent of the United States 10 to O. Mergenthaler, No. 436,531, commonly sold and known in the art under the trademark "Linotype." In these machines the circulating matrices delivered one at a time 15 from the magazine are received upon an inclined carrying-belt and delivered thus successively in front of a vertical "star-wheel" or pusher, which acts against their side faces and pushes them successively and laterally 20 into an assembler, where they are composed or assembled in line against a horizontally-yielding resistant.

Heretofore the star-wheels of square or triangular form have been constructed in one 25 solid piece, their outermost points or corners acting against the matrices. As these wheels are driven at high speed and encounter considerable resistance it is found that they 30 wear away rapidly, so that they are diminished in diameter. In setting certain classes of matter it is important that the wheels shall retain their original and maximum diameter in order that the length of the composed line and the location of certain matrices therein may be accurately determined. 35 To this end I construct a star-wheel provided at its outermost points with one, two, or more freely-revolving bars of angular cross-section, so that as the wheel is rotated 40 the successive bars will be brought into action against the matrices, each bar presenting one or another of its flat faces against a matrix, so that it will slide thereover with more or less frictional effect, in consequence 45 of which it will tend to draw the matrix down to a proper level in the line, while at the same time urging the matrix forward against the line and finally urging the entire line endwise.

50 The employment of the freely-rotating angular bars is advantageous in that each bar presents a number of faces any one of which may come into action, so that the wear is widely distributed. The matrices descend

in an inclined or angular path and are gradually turned to an upright position as they join the line. As each of the rotary bars encounters a matrix its face is seated against the same, so that it acts with a pushing and drawing effect, and as the angle of the matrix changes the bar, turning about its pivot, is permitted to maintain a close or flat contact against the matrix until the latter reaches its final position.

In the drawings, Figure 1 is a front elevation of an assembling mechanism containing my improved star-wheel. Figs. 2, 3, and 4 are similar views showing the wheel in the various relations it occupies to the incoming matrices. Fig. 5 is a perspective view of the 65 star-wheel and adjacent parts, the front portions of the frame being removed to expose the parts to view.

Referring to the drawings, A represents the inclined continuously-traveling belt, upon 70 which the matrices B are successively received and from which they are delivered over a stationary guide or support C into the assembling-elevator D, having in its top a channel in which the matrices are assembled 75 side by side in line.

E represents an upright yielding resistant 80 mounted on the forward end of a horizontal slide and serving to support the forward end of the composed line.

F is a vertically-revolving star-wheel 85 mounted opposite the receiving end of the assembler. The matrices, descending successively in front of the star-wheel, are drawn downward and pushed forward successively 90 into the assembler, each matrix being added to the end of the line, and the line is then pushed bodily forward to permit the entrance of the next matrix.

With the exception of the star-wheel the 95 foregoing parts may all be constructed and arranged to operate as usual. This wheel instead of being made a solid angular piece, as heretofore, now consists of a rectangular frame or body, having at its outermost points 100 or corners the four horizontal bars f, mounted to turn freely on horizontal pivots or axes f'. As the star-wheel is rotated these bars are carried around successively in a common circular path in such manner as to act on the side 105 faces of the downcoming matrices. As each bar is free to turn about its own axis within the wheel, it follows that the descending

matrices will be acted upon by the bars, as shown in Figs. 1 to 4, each bar presenting one face or another, as chance may determine, against the matrix. As each bar comes into action its active face will seat itself against the side face of the matrix, and as the latter in descending changes its angular position the bar will turn to correspond and maintain the contact of its entire face with the matrix, upon which it will act with a sliding frictional effect.

It is to be noted that each bar has not only a movement in a circular path—that is to say, a movement of translation or orbital movement—but also an independent movement around its own axis.

In practice it is found that the bars having the flattened faces are very efficient in their action and that they will assemble the matrices at high speed with better effect than the ordinary solid star-wheels, the points of which present but a small surface at a time in contact with the matrices.

My improved star-wheel is advantageous in that each of the rotary bars, presenting a large surface, causes the wear and friction on the matrices to be distributed over a large surface on the star-wheel, so that the wheel may be operated for a great length of time without appreciable wear or change in its diameter.

The wheel with the flattened rotary bars is also advantageous in that each bar presents, throughout the period of its action on the matrix an extended frictional surface in contact therewith.

I am aware that a star-wheel has been provided with round antifriction-rollers, as shown in the application of Samuel Smith, filed October, 1906, Serial No. 338,950, and this I do not claim, my invention being limited to a construction wherein the star-wheel is provided with freely-revolving bars of angular section having a sliding as distinguished from a rolling movement over the surface of the matrices.

Having thus described my invention, what I claim is—

1. In a matrix-assembling mechanism, and in combination with means for delivering matrices successively thereto, a rotary pusher or star-wheel provided with one or more freely-revolving bars of angular cross-section.

2. The matrix pusher or star-wheel provided with freely-revolving bars of angular cross-section.

3. In a linotype-machine, a support for the matrix-line, a yielding resistant for the line, means for delivering the matrices successively toward the assembler, and a rotary pusher provided with one or more freely-revolving bars of angular cross-section.

In testimony whereof I hereunto set my hand, this 5th day of October, 1906, in the presence of two attesting witnesses.

JOHN RAPHAEL ROGERS.
